(57) **CLAIM**

The ornamental design for a coverless indirect LED shop light, as shown and described.

DESCRIPTION

FIG. 1 is a perspective view of a coverless indirect LED shop light in accordance with my invention.

FIG. 2 is a front elevational view of the coverless indirect LED shop light of FIG. 1.

FIG. 3 is a back elevational view thereof.

FIG. 4 is a left elevational view thereof.

FIG. 5 is a right elevational view thereof.

FIG. 6 is a top plan view thereof.

FIG. 7 is a bottom plan view thereof.

FIG. 8 is a cross-sectional plan view thereof along the line VIII-VIII shown in FIG. 3; and,

FIG. 9 is a cross-sectional partial perspective view thereof along the line IX-IX shown in FIG. 1.

The broken lines in the drawings depict portions of the coverless indirect LED shop light that form no part of the claimed design.

The coverless indirect LED shop light is shown with a symbolic break in its length. The appearance of any portion of the coverless indirect LED shop light between the break lines forms no part of the claimed design.
